COMMUNICATION SYSTEM

Willard P. Place, Wilkinsburg, Pa., assignor to
The Union Switch & Signal Company, Swiss-
vale, Pa., a corporation of Pennsylvania

Application February 6, 1934, Serial No. 709,971

7 Claims. (Cl. 250—6)

My invention relates to communication systems, and particularly to carrier telephone systems using suppressed carrier transmission.

An object of my invention is the provision, in systems of the type referred to, of an improved circuit arrangement in conjunction with an electron tube modulator-oscillator for suppression of the carrier which is modulated by the voice frequencies. Another object of my invention is the provision of a similar circuit arrangement in conjunction with an electron tube oscillator for suppression of the reintroduced carrier which is mixed with the incoming sideband for demodulation. Other objects and advantages of my invention will appear as the specification progresses.

In carrier telephone systems using suppressed carrier transmission heretofore proposed, the combination resulting from modulation of the carrier by voice frequencies is applied to a selective network of balanced circuits and the carrier and one sideband are substantially suppressed and the remaining sideband is passed to the communication circuit. The carrier being of relatively large magnitude, its suppression is more difficult and necessitates a relatively elaborate filter arrangement. A balanced modulator-oscillator consisting of two vacuum tubes operating in the conventional push-pull manner has also been proposed for carrier telephone systems for balancing out the carrier but such arrangement requires two vacuum tubes. In my present invention a bridge type circuit arrangement for an electron tube functioning in conjunction with a tuned circuit for generating a carrier current which is to be modulated by voice frequencies is provided. This bridge circuit substantially eliminates the carrier from the output of the tube by confining the carrier to the bridge circuit, and the associated filter needs only to select between the upper and the lower sideband frequencies produced from modulation with the result that the filter network can be of comparatively simple construction. At the receiving location a similar bridge type circuit for the tuned circuit and the electron tube which generate the carrier to be mixed with the incoming sideband for demodulation is provided. This last mentioned bridge circuit operates to substantially eliminate the reintroduced carrier from the receiving apparatus by confining the carrier to the bridge circuit.

I will describe one form of apparatus embodying my invention, and will then point out the novel features thereof in claims.

In the accompanying drawing, Figs. 1 and 2, when taken together constitute a diagrammatic

view of one form of apparatus embodying my invention, and which apparatus is particularly adapted for telephone communication between two locations on a railway train. The apparatus of Fig. 1 is that for transmitting, and the apparatus of Fig. 2 is that for receiving. It will be understood that in practicing my invention both locations will be equipped with the transmitting apparatus of Fig. 1 and the receiving apparatus of Fig. 2 so that two-way operation may be accomplished. Fig. 3 is a diagram illustrating the bridge type circuit arrangement of Figs. 1 and 2.

Although the apparatus of Figs. 1 and 2 may be located at any two points on a railway train, they will be referred to in the following description as being mounted on the locomotive and in the caboose of a freight train, respectively. As stated above, in actual practice, both the locomotive and the caboose will be equipped with the apparatus of Figs. 1 and 2 in order to provide for two-way communication. The communication circuit from one end of the train to the other may take different forms, and preferably is that disclosed in the L. O. Grondahl application for Letters Patent of the United States Serial No. 450,135, filed May 6, 1930, for Electric train signaling systems, and wherewith transmission is accomplished between the two ends of a train through the medium of the traffic rails.

Although a specific adaptation of my invention is here disclosed, it will be understood that I do not wish to limit myself to telephone systems for railway trains, and my invention is equally useful to other telephone systems of the type here involved. The form here disclosed will serve, however, to illustrate the many applications of my invention. As will appear hereinafter, my invention is not limited to telephone communication and may be utilized for the transmission of code messages or for the transmission of control impulses.

Referring to Fig. 1, the reference character MO designates apparatus for generating carrier current of any convenient frequency say, for example, 7000 cycles per second and which is to be modulated by voice frequencies. The apparatus MO comprises an electron tube and a tuned circuit associated therewith by a bridge type circuit arrangement. The electron tube 5 may take different forms and preferably is a pentode having a filament 6, a plate 7, a screen grid 8 and a control grid 9. The filament 6 is heated by a battery 10 in the customary manner and is provided with a cathode grid 11 interposed between the screen grid 8 and the plate 7 to shield the

screen grid from the secondary electron emission from the plate. A tuned circuit 19 consisting of an inductor 12 and a condenser 15 is associated with the tube 5 by having one terminal, the right-hand terminal as shown in Fig. 1, connected with the plate 7 over a wire 16 and its opposite or left-hand terminal connected with the screen grid 8 over a wire 17. A suitable source of current here shown as a battery 13 is connected between a mid terminal 18 of the inductor 12 and the filament 6, the primary winding 14 of a transformer T1 being interposed between the mid terminal 18 and the battery 13. The parts are so proportioned that substantially an equal voltage is applied to the plate 7 and the screen grid 8. The tube 5 is preferably of the pentode type which functions properly with equal voltage applied to the plate and screen grid, such tubes being well-known to the art. The parts are further so proportioned that oscillations take place between the plate 7 and the screen grid 8 through the tuned circuit 19 which oscillations, as stated above, are of a frequency of 7000 cycles per second. It will be understood, of course, that other frequencies could be generated and that the frequency of 7000 cycles per second is assumed by way of illustration only. It is clear that there is current flowing between the plate 7 and the filament 6 and a similar current flowing between the screen grid 8 and the filament 6, tube 5 being preferably of such characteristics that the alternating current components of these currents are of approximately equal magnitude in response to approximately equal voltages impressed upon the plate and screen grid. It will be understood, however, that pentode tubes having characteristics other than that which produces a substantially equal flow of current as the result of equal voltage on the plate and screen grid may be employed if found desirable, the mid terminal 18 of the inductor 12 being so adjusted as to produce a balanced condition. These conductances of the tube 5 may be represented by resistors Rp and Rg connected between the filament 6 and plate 7, and between the filament 6 and grid 8, respectively. To visualize these internal impedances of the tube 5, the fictitious resistors Rp and Rg are shown on the drawing by dotted lines. However, since the internal impedances of the tube 5 will ordinarily vary somewhat with voltage and different individual tubes, actual resistors Rp and Rg may be connected in the circuits at the locations shown if found desirable to do so in order to obtain greater stability.

It is at once apparent that this arrangement between the tube 5 and the tuned circuit 19 forms a bridge circuit, the portions of the inductor 12 on either side of the mid terminal 18 forming two arms of the bridge, and the plate and grid resistors Rp and Rg forming the other two arms of the bridge. In Fig. 3 this bridge circuit is shown diagrammatically that it may be more clearly understood. When oscillations are generated between the plate and the screen grid, the only part of the carrier current flowing in the connection from the mid terminal 18 to the filament 6 is a small part that may be caused by an unbalanced condition of the bridge circuit.

This carrier frequency current is modulated by voice frequencies in the following manner. The control grid 9 of the tube 5 is provided with a circuit including the secondary winding 20 of a transformer T2 and a battery 21. The primary winding 22 of the transformer T2 is included in a circuit which also contains a battery 23 and a

telephone transmitter or microphone M. Hence, vibrations produced by sound impulses in the microphone M cause corresponding variations in the current flowing in the primary winding 22 which variations induce an electromotive force of a corresponding frequency in the secondary winding 20 and this electromotive force, in turn, is impressed between the control grid 9 and the filament 6 of the tube 5. With the instantaneous potential of the control grid 9 with respect to the filament 6 varied at the relatively low voice frequencies produced by sound impulses in the microphone M, the amplitude in the oscillations taking place in the tuned circuit 19 is varied accordingly. It follows, therefore, that the carrier frequency is modulated in accordance with the voice frequencies and, consequently, upper and lower sideband frequencies are produced.

Since most of the carrier is confined to the bridge circuit, and since the voice frequencies are not affected by the bridge circuit, the current flowing through the primary winding 14 of the transformer T1 chiefly consists of voice frequencies and the upper and the lower sideband frequencies. It follows that the electromotive force induced in the secondary winding 24 of the transformer T1 chiefly consists of the sideband frequencies and voice frequencies, only the small unbalanced portion of the carrier being carried over. This electromotive force induced in the secondary winding 24 is conveyed to a band-pass filter BPF so proportioned and adjusted as to pass one sideband with very little attenuation and to substantially suppress all other frequencies, the upper sideband being preferably passed.

The filter BPF may take different forms several of which are well-known to the art and as its specific structure forms no part of my invention, it is shown conventionally only in order to simplify the drawing. It is clear from the foregoing description, however, that the magnitude of the current applied to the band-pass filter BPF will be relatively small, the major portion of the carrier being eliminated by the bridge circuit, and hence this filter may be relatively simple in construction.

The upper sideband frequency passed by the filter BPF is supplied to the communication circuit, in this instance being first amplified to a relatively high energy level. As here shown, the sideband passed by the filter BPF is impressed between the grid 25 and the filament 26 of an electron tube amplifier 27 with the result that the upper sideband frequencies are reproduced in the plate circuit of the tube 27 greatly increased in amplitude. The plate circuit for the tube 27 includes the input side of an amplifier transmitter AT shown conventionally only and preferably consisting of two electron tubes connected to operate in the well-known push-pull manner, and, hence the upper sideband frequencies are further amplified to a relatively high energy level. The output side of the amplifier transmitter AT includes the primary winding 28 of an output transformer T3, the secondary winding 29 of which is adapted to be coupled with the communication circuit through the medium of a pair of inductor coils 30 and 31.

The inductor coils 30 and 31 are mounted on the locomotive in inductive relation with the traffic rails 1 and 1^a, respectively. Normally these inductor coils will be connected with the receiving apparatus on the locomotive to be described later over normally closed contacts 51 and 52 of a circuit controlling selector SW. Reversing this

circuit controlling selector SW to the position indicated by the dotted lines in Fig. 1, transfers the coils 30 and 31 from the receiving apparatus to the secondary winding 29 of the output transformer T3, the circuit being completed over the contacts 56 and 57. In the form here shown the circuit controlling selector SW is manually operated. It will be understood, however, that the selector SW may be automatically operated by suitable coding apparatus and the coils 30 and 31 alternately connected with the receiving and transmitting apparatus should it seem desirable to do so.

Referring to Fig. 2, 33 and 34 are inductor coils mounted on the caboose in inductive relation with the traffic rails 1 and 1^a, respectively. These coils 30 and 31 are connected with an input filter F1 over normally closed contacts 35 and 36 of a manually operated circuit controlling switch SW1. The filter F1 is preferably a band-pass filter, the parts of which are so proportioned and adjusted as to pass a band of frequencies having a width substantially equal to the voice frequency range and to attenuate all other frequencies. In this instance the filter F1 is so proportioned as to pass the upper sideband of the carrier of the apparatus of Fig. 1 modulated by the voice frequencies. That is, the filter F1 passes a band extending from 7500 to 9500 cycles, the carrier having been assumed to be 7000 cycles per second and the voice frequencies being taken as extending from 500 to 2500 cycles. This upper sideband passed by the filter F1 is applied to the input of an amplifier AM and is made to appear in the output circuit of that amplifier greatly increased in amplitude. The filter F1 and amplifier AM may each be any one of several well-known types for such devices and as the specific type of each forms no part of my present invention, they are shown conventionally only for the sake of simplicity. The output of the amplifier AM includes the primary winding 37 of a coupling transformer T4 and hence an electromotive force having a frequency corresponding to the sideband picked up from the traffic rails is induced in the secondary winding 38 of that transformer.

The receiving apparatus of Fig. 2 is provided with a demodulator D which includes a pentode 45 and an associated tuned circuit 49 both preferably similar to corresponding devices of the modulator oscillator MO of Fig. 1. The bridge circuit arrangement by which the tuned circuit 49 of Fig. 2 is connected with the plate 47 and screen grid 48 of the pentode 45 is identical to that described for the tuned circuit 19 and pentode 5 of Fig. 1 and it is thought not necessary to repeat the description. Suffice it to say that the parts are so proportioned and adjusted that oscillations of the carrier frequency of 7000 cycles per second are generated and flow in the bridge circuit, the small unbalanced portion of the carrier only flowing in the primary winding 44 of a transformer T5 interposed between the mid terminal 50 of the inductor 42 and the battery 43. It is clear that this carrier will be mixed with the sideband frequencies induced in the secondary winding 38 of the coupling transformer T4 and applied to the control grid 49, and that there will be produced corresponding upper and lower sidebands. The lower sideband will consist of the received upper sideband less 7000 cycles, namely, a band ranging from 500 to 2500 cycles, it being recalled that the upper sideband consists of 7500 to 9500 cycles. In other words, this lower sideband will correspond to voice frequencies.

The upper sideband resulting from the mixing of the local carrier with the received upper sideband frequencies will consist of the received sideband plus 7000 cycles. The combination produced by the mixing of the local carrier with the received sideband will appear in the primary winding 44 of the transformer T5 and will induce an electromotive force of corresponding frequencies in the secondary winding 53 of that transformer. The secondary winding 53 is connected with the input side of a band-pass filter F3 having parts so proportioned and adjusted as to pass the voice frequencies and to substantially suppress the remaining products of demodulation. The voice frequencies passed by the filter F3 are then applied to a telephone receiver here shown as a loud-speaker LS, after having been first amplified by an amplifier AM1 of the usual type and whose output circuit includes the primary winding 54 of a transformer T6, the secondary winding 55 of which is connected with the operating winding of the loud-speaker LS.

To describe the operation of my system as a whole I shall assume that the circuit controlling switches SW and SW1 occupy the position illustrated on the drawing with the result that the receiving apparatus on the locomotive and the caboose are both coupled with the communication circuit. As stated hereinbefore, both locations will be provided with the transmitting apparatus and the receiving apparatus of Figs. 1 and 2, respectively. To telephone from the locomotive to the caboose the operator on the locomotive will reverse the circuit controlling switch SW and speak into the microphone M. The upper side band is then supplied to the traffic rails through the medium of the inductor coils 30 and 31 having first been amplified, however, to a relatively high energy level. The transmitted upper side band frequencies will be picked up from the traffic rails at the caboose by the inductor coils 33 and 34 and impressed upon the filter F1 since the switch SW is now in the position for connecting the coils 33 and 34 to the receiving apparatus. After amplification the received sideband frequencies are demodulated and the resulting voice frequencies are supplied to the caboose loud-speaker. To permit conversation from the caboose to the locomotive the caboose operator will shift the circuit controlling switch SW1 to the position for connecting the inductor coils 33 and 34 with the transmitting apparatus on the caboose and the locomotive operator will restore the circuit controller SW to the position illustrated for connecting the receiving apparatus on the locomotive with the inductor coils 30 and 31. From this point on the operation will be similar to that already described in telephoning from the locomotive to the caboose.

While a telephone system has been described, it is clear that by replacing the microphone M with a generator adapted to supply a predetermined frequency within the voice frequency range, say for example, a frequency of 1000 cycles per second, and then coding this current according to a prearranged code, the loud-speaker at the other location will sound a note corresponding to the prearranged code and code messages can be communicated between the two locations. Furthermore, by replacing the loud-speaker LS with tuned circuit networks selectively responsive to different low frequencies within the voice frequency range, an automatic control can be established between the two locations.

Although I have herein shown and described

only one form of apparatus embodying my invention, it is understood that various changes and modifications may be made therein within the scope of the appended claims without departing 5 from the spirit and scope of my invention.

Having thus described my invention, what I claim is:

1. In combination; an electron tube provided with a cathode, a plate and two grids; a tuned 10 circuit having opposite terminals connected one directly to said plate and the other directly to one of said grids and said circuit including an inductor, circuit means for connecting a mid-terminal of said inductor with said cathode, a current source disposed in said circuit means to supply substantially equal voltages to said plate and said one grid for causing oscillations of a predetermined carrier frequency to be generated by the tuned circuit and balanced out of said 15 circuit means, means for varying the potential of the other grid of the tube with respect to the cathode at a given frequency for modulating said oscillations whereby side bands corresponding to said carrier modulated at said given frequency 20 flow in said circuit means with the carrier frequency substantially eliminated, and means coupled with said circuit means for receiving said side bands.
2. In combination; an electron tube provided 25 with two grids as well as a plate and a cathode, a tuned circuit having opposite terminals connected one directly to said plate and the other directly to one of said grids and said circuit including an inductor, a circuit connection for connecting a mid-terminal of said inductor with the cathode to form a bridge circuit consisting of the two portions of said inductor and the tube impedances existing between the plate and the cathode and between said one grid and the cathode, a source of current interposed in said circuit 30 connection to supply voltages to the plate and said one grid for causing oscillations of a predetermined carrier frequency between the plate and said one grid through the tuned circuit and which are balanced out by said bridge circuit, means for impressing between the other grid and the cathode a side band telephone current whereby side band frequencies resulting from demodulation 35 flow in said circuit connection with the carrier frequency substantially eliminated, receiving apparatus including a loud-speaker and a filter adapted to pass voice frequencies, and a transformer having one winding interposed in said circuit connection and a second winding connected with the input terminals of the filter of the receiving apparatus.
3. In combination with telephone receiving apparatus including a first filter adapted to pass a given side band of a predetermined carrier frequency modulated with voice frequencies, a second filter adapted to pass voice frequencies and a loud-speaker connected with the output side of said second filter; an electron tube having two grids as well as a plate and a cathode, a tuned 40 circuit including an inductor and a condenser and tuned to resonance at said predetermined carrier frequency, means to connect one terminal of said tuned circuit directly to the plate and a second terminal of said circuit directly to one of the grids of said tube, means including a source of current for connecting a mid-terminal of said inductor with the cathode of said tube for causing the tuned circuit to produce oscillations of said carrier frequency and for suppressing said carrier 45 frequency in the connection between said mid-

terminal and cathode, means to connect the output side of said first filter between the other grid and cathode of the tube, a transformer having one winding interposed in the connection between said mid-terminal and the cathode and a second winding connected across the input terminals of said second filter, and means for at times connecting the input terminals of the first filter with a communication circuit. 5

4. In combination, a communication circuit, a filter adapted to pass a given side band of a carrier of predetermined frequency modulated with a signaling frequency, means to connect at times the input terminals of said filter with said circuit; an electron tube provided with a cathode, a plate and two grids; a tuned circuit including an inductor and a condenser and tuned to resonance at said predetermined carrier frequency, means to connect one terminal of said tuned circuit directly to said plate and a second terminal directly to one of said grids, other means including a source of current for connecting a mid-terminal of said inductor with said cathode for causing said tuned circuit to produce oscillations of said carrier frequency and for suppressing said carrier frequency in the connection between said mid-terminal and cathode, a transformer having one winding interposed in the connection between said mid-terminal and cathode, receiving means including a signaling device responsive to said signaling frequency and a filter adapted to pass such frequency and connected to a second winding of said transformer, and means to connect the output terminals of the first mentioned filter with the other grid and cathode of said tube. 20

5. In combination; an electron tube provided with a cathode, a plate and two grids; a tuned circuit having one terminal connected directly to said plate and a second terminal connected directly to one of said grids and including an inductor, circuit means for connecting a mid-terminal of said inductor with said cathode to form a bridge circuit consisting of the two portions of said inductor and the tube impedances existing between said plate and the cathode and between said one grid and the cathode, a source of current interposed in said circuit means to supply substantially equal direct current voltages to said plate and said one grid for causing oscillations to take place between the plate and said one grid through the tuned circuit, and means for impressing upon the other grid of the tube the frequencies of a signaling current to vary the amplitude of said oscillations as a function of the instantaneous value of the signaling current to cause current of the resultant side band frequencies with the carrier suppressed to flow between said mid-terminal and said cathode. 45

6. In combination; an electron tube provided with a cathode, a plate and two grids; a tuned circuit having its opposite terminals connected one directly to the plate and the other directly to one of said grids and including an inductor, circuit means for connecting a mid-terminal of said inductor with said cathode, a current source disposed in said circuit means to supply voltage to said plate and said one grid for causing the tuned circuit to generate a predetermined carrier frequency current, means for varying the potential of the other grid of the tube with respect to the cathode at the frequency of a signaling current to vary the amplitude of the carrier current as a function of the instantaneous value of the signaling current to produce in said circuit means the resultant side band frequencies with the car- 70 75

rier frequency eliminated, and means coupled with said circuit means for receiving said side bands.

7. In combination; an electron tube provided with a cathode, a plate and two grids; a tuned circuit having its opposite terminals connected one directly to said plate and the other directly to one of said grids and including an inductor, circuit means for connecting a mid-terminal of said inductor with the cathode to form a bridge circuit consisting of the two portions of said inductor and the tube impedances existing between the plate and the cathode and between said one grid and the cathode, a source of current interposed in said circuit means to supply voltage to

the plate and said one grid for causing oscillations of a predetermined carrier frequency between the plate and said one grid through the tuned circuit, means for varying the potential of the other grid of the tube with respect to the cathode at a given frequency to vary the amplitude of said oscillations as a function of the instantaneous value of said given frequency to produce in said circuit means the resultant side band frequencies with the carrier frequency substantially eliminated, and means coupled with said circuit means for receiving said side bands.

WILLARD P. PLACE.
